C. A. Maguire,

UNITED STATES PATENT OFFICE.

CHARLOTTA A. MAGUIRE, OF CHICAGO, ILLINOIS.

GARMENT-STAY.

1,035,983.

Specification of Letters Patent. Patented Aug. 20, 1912.

Application filed September 15, 1911. Serial No. 649,518.

To all whom it may concern:

Be it known that I, CHARLOTTA A. MAGUIRE, a citizen of the United States, residing at Chicago, in the county of Cook and

5 State of Illinois, have invented certain new and useful Improvements in Garment-Stays, of which the following is a specification, reference being had to the accompanying drawings.

10 My invention relates to new and useful improvements in garment stays and more particularly to a corset stay, and my object is to provide a device of this character with improved means for securing the same to the garment.

15 A further object of the invention resides in providing a stay having a flexible means thereon intermediate of its ends for securing the same to the casing of the corset, and 20 a still further object of the invention resides in providing means at the ends of the stay for securing the same to the corset.

25 Still another object of the invention resides in providing notches in the side edges of the stay adjacent its ends, which are adapted to receive the thread by which the stay may be secured to the garment, and a further object resides in providing openings at the ends of the stay with which may be 30 connected any desired means for additionally securing the stay to the garment.

35 A still further object resides in providing a device which is extremely simple in construction, thereby readily and cheaply manufactured, one which when once applied, will positively remain in its desired position, and one which is extremely effective and useful in operation.

40 With these and other objects in view, my invention consists in the novel features of construction, combination and arrangement of parts as will be hereinafter referred to and more particularly pointed out in the specification and claim.

45 In the accompanying drawing forming a part of this application, Figure 1 is a top plan view of the stay. Fig. 2 is a longitudinal section as seen on line 2—2, Fig. 1, and Fig. 3 is a transverse section as seen on 50 line 3—3, Fig. 1.

55 In carrying out my invention, I shall refer to the drawing in which similar reference characters designate corresponding parts throughout the several views and in

1 indicates the stay proper formed of a

pair of metallic or other strips alined and held together at their ends by means of the usual or any preferred clips or caps 2. The stay or body portion 1 of the device is covered with paper or any other desired material 3 which will prevent the metal of the stay from contacting with the material of the garment, and said stay has the side edges immediately adjacent the ends thereof, provided with the notches 4, said notches being formed so as to receive therein the ends of the caps 2 and also adapted to receive therein the thread (not shown) for securing the stay to the garment. These notches 4 may be the sole means provided on the stay for aiding in the securing of said stay to the garment, if desired, but I have also provided adjacent each end of the stay, a pair of openings 5, said openings being arranged in alinement and adapted to receive therein the thread or any other desired means for securing the device to said garment. If desired, the notches may be eliminated and only the openings 5 used as a means for securing the stay to the garment, but it will be seen that by using both means, the same may be more readily and securely held, and in using both means on one stay, I desire to preferably dispose the pairs of openings in such a manner that one opening is on each side of the horizontal plane of the alining notches which will allow said openings to coöperate with the notches in the use of the thread for securing the device. I have also provided an additional means for securing the stay to the garment intermediate of its ends, which means consists of a short flexible strip 6, preferably tape, riveted, as shown at 7, to the stay in a plurality of places. 80 This flexible strip 6 is preferably positioned to one side of the central portion of the stay, and it will be seen that this portion 6 may be readily sewed or otherwise attached to the casing of the corset to secure the stay 85 thereto intermediate of its ends.

80 It is a well known fact that the present means for securing stays in a corset are a source of trouble, and it will be appreciated that with my improved means for securing stays to a garment, the many difficulties which have heretofore been experienced, will be obviated. It will further be seen that by providing notches in the side edges of the stay adjacent the ends thereof, a ready 90 means is provided for the reception of a thread to attach said ends to a garment, and 95 100 105 110

it will still further be seen that by the additional provision of a pair of openings at each end of the stay, said stay may be more readily secured with less chance of disengagement from the garment. It will still further be seen that I have provided a means intermediate of the ends of the stay for securing the same to the garment and that this means comprises a flexible strip, preferably 5 a tape, which may be sewed or otherwise attached to the casing of the corset. It will still further be seen that my device, in all, is one of very simple and economical construction, whereby the same may be readily 10 and cheaply manufactured, and one which is very effective and useful in operation.

What I claim is:—

A corset stay, comprising a spring strip provided adjacent its ends with oppositely arranged notches in the side edges thereof and also provided with an opening on each side of a line connecting said notches and closely adjacent thereto, said strip also provided intermediate its ends with a piece of fabric permanently secured thereto and extending transversely slightly beyond the edges of the strip.

In testimony whereof I hereunto affix my signature in the presence of two witnesses. 20 25

LOTTIE A. MAGUIRE.
